[57] CLAIM

The ornamental design for a pipe hanger, as shown and described.

DESCRIPTION

FIG. 1 is a front elevational view of a pipe hanger showing my new design with the rear view being a mirror image thereof;

FIG. 2 is a right side elevational view, the opposite side being a mirror image thereof; and,

FIG. 3 is a front elevational view thereof shown in an altered position.

The characteristic feature of the pipe hanger is its U-shaped pipe receiving section formed with a continuous undulating pipe receiving surface.

The broken line showing of a pipe is for illustrative purposes only and forms no part of the claimed design.

FIG. 1

FIG. 2

FIG. 3
